DIAMOND DRILL CORE HOLDER

John Williams McBean, Swastika, Ontario, Canada

Application July 9, 1956, Serial No. 42,180

Term of patent 14 years

(Cl. D58—13)

The rear and other side views of the holder, not shown, are the same respectively as the front and side views shown.

I claim:

The ornamental design for a diamond drill core holder as shown and described.
